UNITED STATES PATENT OFFICE.

EDWARD CLADEL, OF NEW YORK, N. Y.

SANITARY GARBAGE-CAN.

1,093,536.

Specification of Letters Patent. Patented Apr. 14, 1914.

Application filed March 28, 1913. Serial No. 757,449.

To all whom it may concern:

Be it known that I, EDWARD CLADEL, a citizen of the United States, residing at New York city, in the county of New York and State of New York, have invented new and useful Improvements in Sanitary Garbage-Cans, of which the following is a specification.

The general object of the invention is to improve the construction of sanitary garbage cans, in point of cover positioning and cover adjusting properties. And to this end the invention resides in providing for the cover a mount which consists of movable elements adapted for admitting of vertical and lateral movement of the cover in the act of positioning it upon or removing it from the mouth of the can, one of such members being spring-actuated, whereby to effect the proper positioning of the cover when the same is inadvertently displaced on the mouth of the can.

Other objects will appear and be better understood from that embodiment of my invention of which the following is a specification, reference being had to the accompanying drawings, forming part hereof in which:—

Figure 1 is a side elevation of the device. Fig. 2 is a detail vertical cross section of the upper portion of the can looking at right angles to Fig. 1.

The sanitary garbage can herein shown and indicated by *a* may be formed of any material found suitable for the purpose, as metal, and comprises a cylindrical body 5, a top or cover 6 and the cover positioning means forming the subject-matter of the present invention and designated generally by *b*.

The cover 6 is formed with a depending rib or flange 7 which, when the cover is positioned as shown in Figs. 1 and 2, operates by bearing on the inner surface of the body 5 to prevent lateral displacement of the cover until by lifting such cover, the flange is positioned beyond the upper edge of the body. The cover is also formed with a peripheral bearing flange 8, which, when the cover is positioned as shown in Figs. 1 and 2, bears on the upper edge of the body 5.

The cover positioning means includes a pair of brackets *c*—*c* disposed diametrically of the body and connected by suitable pivots

9—9 to suitable hangers 10—10 fastened to the body 5. Each bracket *c* includes outwardly directed offset portions 11—11 arranged in spaced relation and providing ends for a cylinder 12 passed between them. These offset portions 11—11 are bored to 60 loosely receive a piston rod 13, as shown in Figs. 1 and 2.

Referring now to Figs. 1 and 2 the cover is provided with lugs 14—14 which project beyond the periphery of the cover and 65 are diametrically disposed, positioned and pierced so as to receive the upper ends of the rods 13—13. Suitable fastening means herein shown in the form of nuts 15, are employed for fastening the rods to the lugs. 70 The lugs may form part or be otherwise suitably connected to the cover, or as shown in the drawings, they may form extensions of the bail or handle 16 which is suitably fastened to the cover as by rivets 17. 75

Stops 18 are arranged on the lower ends of the rods 13 and operate by moving into contact with the lower offset portions 11, to limit the outward movement or displacement of the rods. The amount of movement afforded to the rods by the stops 18 is sufficient to admit of lifting the cover to a position where the flange 7 will be beyond the upper edge of the body and of moving the cover laterally to a position where it 80 may be tilted out of the vertical plane of the body and moved downwardly to the position shown by dotted lines in Fig. 1. This construction admits of readily discharging the contents of the can when the can is tilted 85 into a garbage wagon. 90

Located within the cylinders 12 and surrounding the rods 13—13 are compression springs 19—19 which are compressed by the heads 20—20 on the rods 13—13 when the 95 cover is lifted and moved laterally as just described. Since any amount of upward movement on the part of the cover will effect the tensioning of the springs 19—19 it will be manifest that in the event of lifting the cover and moving it out of alignment with the body to a considerable degree and then releasing the cover, the flanges 7—7 will first contact with the upper edge of the body and thereby prevent the relaxation of 100 the springs 19—19 so that the springs thus tensioned will exert a downward pull on that part of the cover overhanging the mouth of 105

the can, thus causing the cover to turn on the edge of the can and move to its normal closed position.

What is claimed as new is:

- 5 A can comprising a body, two sets of brackets pivotally mounted one at each side of the body, upon pivots which are common to both members of the sets of brackets, the brackets of each set having spaced end portions, a cylinder located between the said end portions of the brackets of each set, a cover having lugs, rods adjustably attached
- 19

to the lugs and passing through the cylinders and the end portions of the brackets and a spring located in each cylinder and bearing at one end against the end portion of one bracket of each set, said springs being operatively connected with the rods. 15

In testimony whereof I affix my signature in presence of two witnesses.

EDWARD CLADEL.
